UNITED STATES PATENT OFFICE.

PHILIP PHILIPSEN, OF NEW YORK, N. Y.

DESIGN FOR A MEDAL.

SPECIFICATION forming part of Design No. 22,556, dated June 27, 1893.

Application filed March 28, 1893. Serial No. 468,045. Term of patent 3½ years.

To all whom it may concern:

Be it known that I, PHILIP PHILIPSEN, a citizen of the United States, residing at New York, county and State of New York, have 5 invented and produced a new and original Design for a Medal Commemorative of the Discovery of America, of which the following is a full, clear, and true description and the accompanying drawings a representation.

10 In the drawings Figure 1 is an obverse, and Fig. 2 is a reverse view of my design.

The obverse which is illustrated by Fig. 1 exhibits a circular disk upon the rim of which is shown a series of triangular shaped points 15 approximately duplicating the markings for points and fractions of points upon the face of the mariner's compass. At each quadrant of the disk the cardinal points are designated by letters. Within the rim are exhibited two 20 figures, one a man, the other a female; the male figure stands upon the deck of a ship and grasps a rudder tiller in his hand. The female figure is slightly raised from the deck of the vessel and points to the west on the 25 rim of the circle with her right hand and clasps with her left the right hand of the man. Above the head of the female is a star with rays. The allegory sought to be represented is the Genius of Discovery inciting Columbus 30 westward. The essential elements of the design for the obverse of my medal, are the compass points, cardinal points, male and female figures, deck of the vessel, tiller and star.

35 The reverse view of my medal design rep-

resents a spread eagle, having in his beak a ribbon. In the talons of the eagle are three arrows and an olive branch. Upon the breast of the eagle is a shield with stars and stripes upon it. The eagle rests upon a tablet parallelogram in form, upon which is a leaf ornamentation extending across the top and falling down on each side. Scroll work is shown on all sides of the tablet. At the lower portion of the medal a view of a building is 40 shown, with a dome and two towers, and a wreath of leaves forming the segment of a circle forms the border on two sides of the building. Upon this reverse side of the design a double line forms the perimeter. 45

The essential features of the reverse of the design are the eagle, tablets with inscription and view of buildings. 50

In the drawings A is the compass points, B, B, the four cardinal points, D the male figure, E the female figure, F the rudder tiller, E the star with rays, G the eagle with shield on the breast, ribbon in beak, arrows and olive branch in talons, H the tablet, K the inscription, L the leaf ornamentation, M the scroll work on sides and top, N the buildings, and O the wreath. 55

I claim—

The design for a medal as herein shown and described.

PHILIP PHILIPSEN.
